UNITED STATES PATENT OFFICE.

LOUIS BRYANT, OF CANTON, MISSISSIPPI.

RAIL JOINT.

Application filed July 23, 1923. Serial No. 653,124.

To all whom it may concern:

Be it known that I, LOUIS BRYANT, a citizen of the United States, residing at Canton, in the county of Madison and State of Mississippi, have invented certain new and useful Improvements in Rail Joints, of which the following is a specification.

This invention relates to certain new and useful improvements in rail joints, and has 10 particular reference to devices of that kind known as scarf joints.

An object of the invention is to provide a durable and simple form of joint which eliminates the necessity of employing separate fish plates or like joining members.

Another object of the invention is to provide a scarf joint by means of which considerable pounding at the joints is prevented, through the use of which expansion and 20 contraction is taken care of, and by means of which a durable joint is had.

Other objects will appear as the nature of the invention is better understood, and the same consists in the novel form, combination and arrangement of parts herein-after more fully described, shown in the accompanying drawing and claimed.

In the drawing, wherein like reference characters indicate corresponding parts 30 throughout the several views,

Figure 1 is a side elevational view of a rail joint constructed in accordance with the present invention,

Figure 2 is a top plan view, partly broken 35 away and in section, of the device shown in Figure 1,

Figure 3 is an elevational view of one of the rail ends,

Figure 4 is a top plan view of the device 40 shown in Figure 3, and

Figure 5 is transverse sectional view through the rail joint shown in Figure 1 adjacent the fastening bolts thereof.

Referring more in detail to the invention, 45 the same embodies the provision of rail ends 5 and 6 which consist in substantially vertical half-sections of the rail ends arranged in overlapping relation and provided with thickened web portions 7 which are reduced 50 in height at their free ends as at 8 and also in thickness so as to overlap the web 9 of the rail. The overlapping end 6 is formed with

a plurality of screw threaded openings as at 10 into which are threaded bolts 11 which extend freely through horizontal longitudinally elongated slots 12 provided in the other end 5, the heads of the bolts 11 being of greater width than the slot 12 so that when said bolts are tightened, the overlapping ends 5 and 6 are maintained in contiguous relation although capable of sliding longitudinally relative to each other. In order to prevent turning of the bolts 11 out of the opening 10, or in other words, in order to effectively prevent accidental displacement of the bolts for destruction of the rail joint, means is provided for retaining these bolts against rotation and the same consists in suitable pins 13 which are driven through oblique openings 14 in the heads of the bolts 11 to and into the slot 12 of the rail ends 5.

It will be seen that a rail joint constructed in accordance with the above eliminates the necessity of employing objectional nuts and separate fish plates or the like, and provides a very durable joint capable of being easily and quickly assembled without the requirements of special tools or skilled labor.

It will be noted that the construction provides for the ready expansion and contraction of the joined rails, and the advantages of the invention will become readily apparent to those skilled in the art from the above.

Minor changes may be made without departing from the spirit and scope of the invention as claimed.

What I claim as new is:—

A scarf rail joint including a pair of rail sections having reduced ends disposed side by side in overlapped relation and longitudinally movable on each other, one of said ends being provided with horizontal longitudinally elongated slots, the other of said ends being provided with screw threaded sockets, bolts passing loosely through said slots and threaded into said sockets, and means associated with the slotted rail end and the heads of the bolts for preventing accidental rotation of the latter, said last named means embodying keys passing through oblique openings in the heads of the bolts and entering the slots of said rail ends.

In testimony whereof I affix my signature.
LOUIS BRYANT.
